Primary Examiner — Catherine Tuttle(74) Attorney, Agent, or Firm — Volpe and Koenig, P.C.CLAIM

The ornamental design for a cheese wedge container, as shown and described.

DESCRIPTION

FIG. 1 is a top, front right perspective view of the cheese wedge container in accordance with my design;

FIG. 2 is a front elevational view thereof;

FIG. 3 is a rear elevational view thereof;

FIG. 4 is a top plan view thereof;

FIG. 5 is a bottom view thereof;

FIG. 6 is a right side elevational view thereof; and,

FIG. 7 is a left side elevational view thereof.

The broken line shown in FIGS. 1 and 6 is for illustrative purposes only; and forms no part of the claimed design.
